UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO.

MEANS FOR OPERATING PRESSES.

Application filed November 19, 1921. Serial No. 516,508.

To all whom it may concern:

Be it known that I, FRANCIS E. STEVENSON, a citizen of the United States, residing at Mount Gilead, in the county of Morrow and State of Ohio, have invented certain new and useful Improvements in Means for Operating Presses, of which the following is a specification.

This invention relates to presses of the type in which one press member or platen is moved toward the other by fluid pressure, and in which the movable member is supported by a large ram that is initially moved by a small ram.

One object of the invention is to operate the movable member of the press rapidly by using a small quantity of fluid from the pump in connection with the small ram while the resistance is small, and automatically applying high pressure to both rams when a certain degree of pressure is met.

Another object is to provide valve mechanism and connections that will permit the use of a simple pump without low pressure plungers, but yet will give in effect the action of a high and low pressure pump without any danger of hammering the suction valves which often occurs in presses of this type.

Another object is to provide mechanism that may be easily started and released, and which may also be stopped before completion of the press movement without releasing the pressure already applied to the rams.

A further object of the invention is to provide an expanding packing in engagement with the large ram which will efficiently prevent leakage of air past the ram, but readily permit idle movements of the ram.

These and other objects are attained by the mechanism hereinafter described and covered by the appended claims.

In the drawings:

Figure 1 is a diagrammatic view of the mechanism with parts in section;

Figure 2 is a cross section of the rams showing the packing and fluid pipe leading thereto;

Figure 3 is a detail vertical section of the expanding packing and related parts;

Figure 4 is a vertical section through valve chamber on line 4-4 of Figure 1;

Figure 5 is a vertical section through the valve casing on the line 5-5 of Figure 1;

Figures 6 to 10 inclusive are section and perspective views, each similar to Figures 4 and 5, and showing both sets of valves in their positions at different stages of the operation;

Figure 6 shows the position of the parts during the first portion of the operation, the fluid then passing from the pump through pipe 21, passage 22, valve 13 and pipe 10 to small cylinder or chamber 8, also through passage 27 to under side of valve 16, which has not yet opened. At the same time, fluid is drawn from reservoir through pipes 24 and 26, valve 15 and pipe 9 to the large cylinder or chamber 7.

Figure 7 shows the position of the parts immediately following that of Figure 6, when the pressure has opened valve 16, the fluid then passing to small chamber 8 in the same manner, and to large chamber 7 from pump through pipe 21, passage 22, valve 13, passage 27, valve 16 and pipe 9. Valve 15 closes as soon as valve 16 opens, on account of pressure above it.

Figure 8 shows the position of the parts after the completion of the press operation when valve 14 has been opened by manual movement of lever 30. The fluid then flows back from small chamber 8 through pipe 10, valve 14, and pipes 25 and 24 to reservoir. The fluid from large chamber 7 flows through pipe 9, valve 16, passage 27, valve 13, valve 14, and pipes 25 and 24 to reservoir.

Figure 9 shows the position of parts when the lever 30 has been further operated to open valve 15. The fluid from small chamber 8 follows the same path as in Figure 8, but the fluid from the large cylinder flows through pipe 9, valve 15 and pipes 26 and 24 to the reservoir.

Figure 10 shows the position of the parts when operation is stopped by a manual actuation of lever 33 and consequent opening of valve 12. The fluid from the pump then flows through pipe 21, passage 22, valve 12 and pipe 23 back to reservoir. At the same time valve 13 and valve 15 (if open) are seated by back pressure, thus retaining the pressure already applied to the rams.

The press comprises upper and lower members or platens, the upper member 1

being here shown as stationary, and the lower member 2 as movable. Between these is the work A. There is also shown diagrammatically a pump 3 and a reservoir 4. 5 These parts may be of any desired construction.

The movable member of the press is carried by a compound ram comprising a large ram 5 and a small ram 6 which slide in 10 chambers or cylinders 7 and 8 respectively. The fluid supplied to the chamber 7 through a pipe 9, and to chamber 8 through a pipe 10. A valve casing 11 contains two groups of valves, one group comprising valves 12, 15 13 and 14, shown in Figure 5, and the other comprising valves 15 and 16, shown in Figure 4. The valves 12, 14 and 16 are held normally closed by springs 17, 18 and 19 respectively, but the valves 13 and 15 are free 20 to open upon pressure on their under sides. A pipe 20 connects the pump with the reservoir and a pipe 21 connects pump with passage 22 which communicates with under side of the valves 12 and 13. A return pipe 23 leads from upper side of valve 12 back to reservoir. A pipe 24 leads from reservoir and communicates by means of branches 25 and 26 with the under side of valves 14 and 15 respectively. A passage 27 30 leads from above valve 13 to the under side of valve 16.

The pipe 9 leads from the large cylinder 7 to the chamber in which are located the valves 15 and 16, while the pipe 10 leads 35 from the small cylinder 8 to the chamber containing valves 13 and 14.

The valves 14 and 15 have depending stems 28 and 29 respectively, which overlie a lever 30 pivoted at 31 and manually operated through a connection 32. This lever is wide enough to raise both stems when actuated but the stems are of different lengths so that they are operated in sequence. The stem 28 is longest and normally rests on lever 30 while the stem 29 is out of engagement therewith. It is desirable not to open valve 15 first because it is larger than valve 14 and cannot be lifted easily until the pressure is reduced.

50 A lever 33 pivoted at 34 is connected to valve 12 and may be manually operated by a connection 35 whenever it is desired to open valve 12 for purposes hereinafter set forth.

55 The operation of the parts thus far described is as follows:

Assuming that the press is open and ready for an operation, and that all valves are closed as in Figures 4 and 5, the pump 60 delivers the fluid through pipe 21 to passage 22. The safety valve 12 is held closed by its spring 17, but the valve 13 is free to rise under the pressure of the fluid. This permits the fluid to flow around the stem 65 of the valve 14 and out of the pipe 10 which

delivers the fluid to the cylinder 8 to operate the small ram 6.

The first movement of the small ram 6 also moves the large ram 5 and tends to produce a vacuum in cylinder 7. This 70 draws in fluid from the reservoir through pipes 24 and 26, valve 15 and pipe 9, since the suction in pipe 9 opens valve 15 which is free to move.

At the same time the fluid flows from 75 above the valve 13 through passage 27 to under side of valve 16, which, however, is held closed during the first part of the operation by its spring 19.

At this time the parts occupy the position 80 shown in Figure 6, with the fluid moving as there indicated.

Since the chamber above valve 13 communicates by passage 27 with the chamber below valve 16, it is evident that the pressure tending to open valve 16 is the same as that applied to the small ram 6. As increasing resistance is offered to the rising of the ram 6, the pressure ultimately reaches 90 a point where the spring 19 is overcome and the valve 16 is opened. The pump discharge is then applied directly to large ram, the fluid passing from pump through pipe 21, passage 22, valve 13, passage 27, valve 16 and pipe 9 to chamber 7. As soon as valve 16 opens, the pressure on top of valve 15 closes the same. The fluid is supplied to small chamber 8 in the same manner as above described. At this time the parts occupy the position shown in Figure 7, with 100 the fluid moving as there indicated.

When the proper pressure has been applied and the work performed, it is then necessary to relieve the pressure on the rams and permit the fluid to flow back to the reservoir. The operator, by means of connection 32 lifts the lever 30 enough to open the valve 14 through its stem 28. The fluid then flows back from small cylinder 8 and passes through pipe 10, valve 14, and pipes 25 and 24 to the reservoir. The fluid from the large cylinder 7 flows back through pipe 9 over valve 15, down through valve 16 which is still held open by the pressure in the system, through passage 27, over valve 13, through valve 14 and pipes 25 and 24 to the reservoir. The position of the parts at this time is shown in Figure 8 with the fluid moving as there indicated.

When the pressure is sufficiently lowered, 120 the operator raises the lever 30 farther, opening valve 15 through its stem 29. When this valve is opened, the fluid flows directly from large chamber 7 through pipe 9, valve 15 and pipes 26 and 24 to reservoir. The fluid is flowing from the small chamber 8 to the reservoir through the path shown in Figure 8. At this time, the position of the parts is shown in Figure 9, with 125 the fluid moving as there indicated.

If at any time in the upward movement of the rams 5 and 6, the operator desires to stop them without releasing the pressure already applied, he depresses the connection 35, thereby operating the lever 33 to open the valve 12. This permits the pump discharge to flow through pipe 21, valve 12 and pipe 23 back to reservoir. Under these conditions the back pressure in the connections to the rams seats the valves 13 and 16 and retains the pressure already applied to the rams. The position of the parts at this time is shown in Figure 10, with the fluid moving as there indicated.

If at any time it is desired to allow the press to remain inactive with parts in normal position, this may be done without stopping the pump by latching the connection 35 in any desired manner to hold open the valve 12, thus permitting a free circulation of fluid between pump and reservoir without exerting pressure on the rams.

It is obvious that the spring 17 which holds the valve 12 seated must be of considerably greater strength than the spring 19 which holds the valve 16 seated, since the valve 16 must be automatically opened by a rise in pressure, while the valve 12 is not opened except manually under normal conditions. However, it is evident that under any excessive pressure, the valve 12 would be automatically opened producing the same result as if opened manually. This valve therefore serves as an automatic relief or safety valve.

Surrounding the large ram 5 is an annular chamber 36 in which are located U-shape leather packings 37 normally retained in position by a perforated ring 38. Branching from the pipe 10 which leads to the small chamber 8, is a pipe 39 through which fluid is conducted to the chamber 36.

As the rams 5 and 6 rise, a vacuum is produced in chamber 7 which draws in fluid from the reservoir as above set forth. Any leakage of air around the ram 5 to chamber 7 would cause imperfect operation. But as soon as fluid is admitted through pipe 10 to small chamber 8, it is at the same time admitted to chamber 36 through pipe 39. This expands the leather packings and produces an air tight joint. When the pressure is relieved from the rams to permit them to return to idle position, it is also relieved from the packing, thereby reducing the friction that would be present in the ordinary type of packing.

It is obvious that the invention herein disclosed may be applied to machines of various types, and the illustration of the press, pump and reservoir is to be regarded as merely illustrative and not as limiting the application of the invention.

I claim as my invention:

1. The combination of small and large rams working in small and large cylinders respectively, and a fluid-circulating system for applying pressure thereto comprising a pump, a reservoir, a valve casing, a line of communication from the pump through the valve casing to the small cylinder, a valve in said line freely opened by pressure, a line of communication to the large cylinder branching from said first line, a spring-closed valve therein which opens only after a predetermined pressure has been reached in the first line, and a line of communication branching from said second-named line between the spring-pressed valve and the large cylinder and leading to the reservoir, a valve therein freely opened by suction from the large cylinder but automatically closed as soon as the spring-pressed valve is opened.

2. The combination of small and large rams working in small and large cylinders respectively, and a fluid-circulating system for applying pressure thereto comprising a pump, a reservoir, a valve casing, a line of communication from the pump through the valve casing to the small cylinder, a valve in said line freely opened by pressure, a line of communication to the large cylinder branching from said first line, a spring-closed valve therein which opens only after a predetermined pressure has been reached in the first line, a line of communication between the reservoir and pump passing through the valve casing, a spring-closed relief valve therein, and manually-operated means for opening said valve to stop operation of the press at any time.

3. The combination of small and large rams working in small and large cylinders respectively, and a fluid-circulating system for applying pressure thereto comprising a pump, a reservoir, a valve casing, a line of communication from the pump through the valve casing to the small cylinder, a valve in said line freely opened by pressure, a line of communication to the large cylinder branching from said first line, a spring-closed valve therein which opens only after a predetermined pressure has been reached in the first line, a line of communication between the reservoir and pump passing through the valve casing, a spring-closed relief valve therein, and manually-operated means for opening said valve to stop operation of the press at any time, said valve automatically opening upon the development of excessive pressure in the circulating system.

4. The combination of small and large rams working in small and large cylinders respectively, and a fluid-circulating system for applying pressure thereto comprising a pump, a reservoir, a valve casing, a line of communication from the small cylinder through said valve casing to the reservoir, a line of communication from the pump through the valve casing to the small cylinder, a valve in said line freely opened by pressure, a line of communication to the large cylinder branching from said first line, a spring-closed valve therein which opens only after a predetermined pressure has been reached in the first line, and a line of communication between the reservoir and pump passing through the valve casing, a spring-closed relief valve therein, and manually-operated means for opening said valve to stop operation of the press at any time.

the large cylinder through the valve casing to the reservoir, a spring-pressed valve therein, and manually-operated means for opening said valves to permit the fluid to pass 5 to the reservoir from the cylinders.

5. The combination of small and large rams working in small and large cylinders respectively, and a fluid-circulating system for applying pressure thereto comprising a 10 pump, a reservoir, a valve casing, a line of communication from the small cylinder through said valve casing to the reservoir, a valve therein, a line of communication from the large cylinder through the valve 15 casing to the reservoir, a spring-pressed valve therein, and manually-operated means for opening said valves in sequence to permit the fluid to pass to the reservoir from the cylinders.
- 20 6. The combination of a casing, a ram reciprocating therein, means for supplying pressure thereto, an annular chamber in said casing surrounding said ram, expansive packing in said chamber, and separate means 25 for supplying pressure to said packing to expand the same.
7. The combination of a casing, a ram reciprocating therein, an annular chamber in said casing surrounding said ram, expansive 30 packing in said chamber, means for supplying fluid under pressure to operate said ram, and branch means for simultaneously supplying fluid under pressure to said packing to expand the same.
- 35 8. The combination of a casing, a ram reciprocating therein, means for supplying pressure thereto, an annular chamber surrounding said ram, an annular U-shaped expansive packing member in said annular 40 chamber, and separate means for supplying fluid under pressure to said packing to expand the same.
- 45 9. The combination of a casing, a ram reciprocating therein, an annular chamber in

said casing surrounding said ram, an annular U-shaped expansive packing member in said annular chamber, means for supplying fluid under pressure to operate said ram, and branch means for simultaneously supplying fluid under pressure to said packing to expand the same.

50 10. The combination of a casing, a ram reciprocating therein, an annular chamber in said casing surrounding said ram, opposed U-shaped expansive packing members in said 55 annular chamber, and means for supplying fluid under pressure to said packing members to expand the same.

55 11. The combination of a casing, a ram reciprocating therein; an annular chamber in said casing surrounding said ram, opposed U-shaped expansive packing members in said 60 annular chamber, a ring member normally holding said members in position, and means for supplying fluid under pressure to said packing to expand the same.

65 12. The combination of a casing, a ram reciprocating therein, an annular chamber in said casing surrounding said ram, opposed U-shaped expansive packing members in said 70 annular chamber, a perforated ring member normally holding said packing members in position, means for supplying fluid under pressure to operate said ram, and branch 75 means for simultaneously supplying fluid under pressure to said packing to expand the same.

80 13. The combination of a casing, small and large rams reciprocating therein, an annular chamber in the casing surrounding the large ram, expansive packing in said chamber, means for applying pressure to the small ram, means for supplying pressure to the expansive packing at the same time and before 85 pressure is applied to the large ram.

In testimony whereof, I have hereunto subscribed my name.

FRANCIS E. STEVENSON.
